Des. 193,112
Patented June 26, 1962

193,112

PORTABLE VACUUM FORMING MACHINE

Hugh B. Morse, San Jose, Calif., assignor to Avery Industries, Inc., San Mateo, Calif., a corporation of California

Filed Feb. 3, 1961, Ser. No. 63,814

Term of patent 14 years

(Cl. D54—8)

FIG. 3

FIG. 2

FIG. 1

FIG. 4

FIG. 5

FIG. 6

FIG. 7

FIG. 1 is a front elevation of my new design for a portable vacuum forming machine.

FIG. 2 is a side elevational view showing the left side as viewed from the front.

FIG. 3 is a top plan view.

FIG. 4 is a bottom plan view.

FIG. 5 is a side elevational view showing the right side as viewed from the front.

FIG. 6 is a rear view; and

FIG. 7 is a perspective view showing the top, front and left side of the machine.

The roll of sheet material shown in broken lines in FIGS. 1 and 7 is for illustrative purposes only.

I claim:

The ornamental design for a portable vacuum forming machine, as shown and described.
